DICTATING MACHINE

Eliot Noyes, New Canaan, Conn., assignor to International Business Machines Corporation, New York, N.Y., a corporation of New York

Filed Sept. 12, 1960, Ser. No. 62,094

Term of patent 14 years

(Cl. D26—14)

FIG. 1

FIG. 2

FIG. 3

Fig. 1 is a front perspective view of a dictating machine, showing my new design;

Fig. 2 is another front perspective view, showing the opposite side; and Fig. 3 is a rear perspective view thereof.

The broken line showing a detachable microphone is for illustrative purposes only.

I claim:

The ornamental design for a dictating machine, substantially as shown and described.
